CLAIM

What is claimed is the ornamental design for a knee pillow, as shown and described.

DESCRIPTION

FIG. 1 shows a perspective view of a knee pillow;
FIG. 2 shows a rear plan view of the knee pillow of FIG. 1;
FIG. 3 shows a front plan view of the knee pillow of FIG. 1;
FIG. 4 shows a top view of the knee pillow of FIG. 1;
FIG. 5 shows a bottom view of the knee pillow of FIG. 1;
FIG. 6 shows a left-side view of the knee pillow of FIG. 1; and,
FIG. 7 shows a right-side view of the knee pillow of FIG. 1. The portions of the knee pillow shown in broken lines form no part of the claimed design.
